UNITED STATES PATENT OFFICE.

HARRY F. WAITE, OF NEW YORK, N. Y.

MEANS FOR COOLING VACUUM-TUBES.

1,125,223.

Specification of Letters Patent. Patented Jan. 19, 1915.

Application filed September 22, 1913. Serial No. 791,162.

To all whom it may concern:

Be it known that I, HARRY F. WAITE, a citizen of the United States, residing at New York, in the county of New York and State of New York, have invented certain new and useful Improvements in Means for Cooling Vacuum-Tubes; and I do hereby declare the following to be a full, clear, and exact description of the invention, such as will enable others skilled in the art to which it appertains to make and use the same.

This invention relates to an improved construction of cathodes for X-ray and other high vacuum tubes, and means for cooling the same, and has for its object to do away with the annoyances due to the heating of the present cathodes and the adjacent parts of the tube.

With these and other objects in view the invention consists in the novel details of construction and combinations of parts more fully hereinafter disclosed and particularly pointed out in the claim.

Referring to the accompanying drawings forming a part of this specification in which like numerals designate like parts in all the views:—Figure 1 is a diagrammatic sectional view of an X-ray tube with my invention applied thereto; and Fig. 2 is a cross sectional detail view showing the conducting spring members between the air tube and the cathode.

1 indicates any vacuum tube the cathode or other portion of which it is desired to cool; 2 a metal cathode or other terminal; 3 a metal tube sealed in the cathode 2; 4 a platinum tube sealed to the metal tube 3; and 5 the glass of the tube 1 turned up and sealed to the platinum tube 4.

6 represents a metal cap setting over and secured to the negative end of the tube 1, and provided with the opening 7 to which may be attached the tube 8 as shown. Passing through the cap 6 is the metal tube 9 adapted to be connected at one end with a source of compressed air by the tube 10, and to a source of current by the wire 11 as will be clear from the drawings. To the other end of the tube 9 is secured the spring like conductors 12 preferably three in number, which center said tube and also contact with the metal tube 3, and thereby complete the circuit from the wire 11 to the cathode 2.

14 represents a glass collar surrounding the cathode neck of the tube 1, and fitting snugly the bulb of said tube. Said collar

is provided with the nipple 15 to which the tube 8 may be connected, and also with the rubber gasket 16 which fits the neck of the tube 1, the air in chamber 17 escaping through the opening 18.

The operation of my invention will be clear from what follows:—Owing to the very powerful vacuum tube apparatus now employed, the heating of the cathode and adjacent portions of the tube becomes a serious obstacle to the efficient use of the tubes. By my invention, the current has a continuous metallic connection from the source to the electrode being cooled, the compressed air fed through the tube 9 expands at the points most heated and therefore produces a maximum cooling action at the place needed. After escaping from the tube 9 the compressed air preferably passes back to the opening 7 and through the tube 8 into the chamber 17 whence it escapes through the opening 18 and thereby cools the neck of the tube 1 surrounding the cathode, but, of course, the chamber 17 may be independently supplied with compressed air if desired. It is found that the inside resistance of the tube remains more constant when both the neck and cathode are cooled, than when only one is cooled, and therefore the penetration of the rays is more satisfactory. In fact by my means of cooling these parts, I am enabled to maintain a vacuum sufficiently low to accomplish penetrations that would be impossible with uncooled parts, owing to the great heat that is generated in these said parts.

My invention, of course, is applicable to other vacuum tubes than those used in X-ray work. For example, it is applicable to the so called "valve" tubes wherein two bulbs provided with electrodes of different sizes are connected by a restricted passage. Accordingly, I do not wish to be limited to the above disclosure except as may be required by the claim.

What I claim is:—
In an X-ray tube the combination of a cathode tip; a metal tube connected to said tip; a platinum tube connected to said metal tube; a glass connection with said platinum tube; a metal gas tube adapted to deliver gas to said cathode tip; a metallic connection between said gas tube and said cathode tip, whereby current may be conveyed to said tip through said gas tube; a cap fitting the negative end of said X-ray tube, adapted to

prevent the escape of gas from said negative tip; a chamber surrounding the cathode neck of said negative end; and a connection between said cap and chamber by which cooling gas after leaving the cathode tip is caused to circulate around said neck, substantially as described.

In testimony whereof I affix my signature, in presence of two witnesses.

HARRY F. WAITE.
